PHONOGRAPH RECORD IDENTIFICATION TAB

Everett L. Brownsey, La Porte, Ind.

Application January 20, 1948, Serial No. 3,355

2 Claims. (Cl. 40—23)

1

My invention relates to an identification tab for phonograph records.

An important object of the invention is to provide a detachable identification tab for phonograph records which eliminates the need for handling the records while attempting to locate a particular one in a group.

A further object of the invention is to provide a detachable identification tab for phonograph records which is extremely simple and quite inexpensive to manufacture.

Other objects and advantages of the invention will be apparent during the course of the following description.

In the accompanying drawings, forming a part of this application, and in which like numerals are employed to designate like parts throughout the same,

Figure 1 is a side elevation of the identification tab shown applied to a record,

Figure 2 is a side elevation of the tab removed,

Figure 3 is a view of a partly completed identification tab blank,

Figure 4 is an end edge elevation of the tab as applied in Figure 1.

In the drawings, where for the purpose of illustration is shown a preferred embodiment of the invention, the numeral 6 designates a thin flat relatively stiff side or tab body, having inwardly converging side edges 7, and a rounded inner end 8. At its outer end, the side 6 is circularly curved to conform to the outside diameter of a standard size phonograph record 9, upon which the tab is to be detachably mounted. At its outer circularly curved end, the side 6 is provided with a pair of short flat inwardly projecting portions or flaps 10, substantially parallel to the plane of side 6 and preferably formed integral therewith. The flaps 10 are elongated laterally with respect to side 6, and are connected to the side 6 through integral U-shaped ends 11, forming a substantially continuous circularly curved shoulder to engage the peripheral edge 12 of record 9. The flaps 10 may be tensioned downwardly slightly toward the adjacent surface of side 6, so that the side 6 and the flaps 10 will tend to engage the faces of record 9 with sufficient force to support the identification tab. The U-shaped ends 11 will also tend to produce a clamping or wedging effect upon the edge 12 of record 9, which further facilitates detachably securing the identification tab to the record 9. The flaps 10 are cut near the transverse center of side 6 to form a tab handle 13 which is flat and disposed in the same plane as side 6, and integral with the side.

2

The handle 13 projects radially beyond the ends 11, as shown, and may be provided with a curved outer end 14, if desired. The entire tab is formed from a unitary piece of thin stiff sheet material, such as sheet aluminum, or the like. One or both surfaces of side 6 is provided with the name or designation of the particular record to be identified and this information is printed or otherwise visibly marked upon the side 6, as shown in Figure 1.

In use, the identification tab is applied to a phonograph record, as clearly shown in Figures 1 and 4. The clamping action of side 6 and flaps 10 is sufficient to support the weight of the identification tab, and light enough so that the tab will not tend to scratch the record. The downwardly tensioned tabs 10 do not project radially inwardly beyond the inner diameter of the smooth outer annular band 15 of record 9, which has no sound grooves formed therein. This design precludes scratching of the sound-grooved portion of the record. When an effort is being made to locate a record in a group of records, the handle 13 of the identification tab is grasped and the tab is removed bodily from the record. If the title of the record sought is marked on the tab, the record may be picked up. If the title on the tab is not the one sought, the tab is placed back upon the record and another tab is pulled, until the record sought is located. In this manner, the necessary handling of the records is reduced to a minimum, and this is particularly important in stores where new records are sold.

It is to be understood that the form of the invention herewith shown and described is to be taken as a preferred example of the same and that various changes in the shape, size and arrangement of parts may be resorted to without departing from the spirit of the invention or the scope of the subjoined claims.

Having thus described the invention, I claim:

1. A detachable identification tab for a phonograph record having on either side thereof a smooth outer annular surface band with no sound grooves formed therein comprising in combination, a thin flat relatively stiff tab body arranged in face adjacency with respect to one side of said record and having side edges converging inwardly from the peripheral edge of the record substantially beyond the inner diameter of the surface band on said one side of the record, a thin flat relatively stiff flap arranged on the opposite side of the record in face adjacency therewith and substantially parallel to the plane of said tab body, said flap having an outer curved edge cor-

responding to the peripheral edge of the record and an inner curved edge corresponding to the inner edge of the surface band adjacent thereto, a U-shaped end interconnecting the outer edges of said tab body and said flap and having a substantially continuous curved shoulder in engagement with the peripheral edge of the record, and a tab handle comprising a portion of said tab body projected outwardly therefrom beyond the peripheral edge of the record, said tab body having markings thereon for identifying said record.

2. A detachable identification tab for a phonograph record having on either side thereof a smooth outer annular surface band with no sound grooves formed therein comprising, in combination, a thin flat relatively stiff tab body arranged in face adjacency with respect to one side of said record and having side edges converging inwardly from the peripheral edge of the record a substantial distance beyond the inner diameter of the surface band on said one side of the record and terminating in a rounded inner edge, a pair of thin flat relatively stiff flaps arranged in circumferentially spaced relation on the opposite side of the record in face adjacency therewith and substantially parallel to the plane of said tab body, each of said flaps having an outer curved edge corresponding to the peripheral edge of the record and an inner curved edge corresponding to the inner edge of the surface band adjacent thereto, a pair of U-shaped ends respectively interconnecting the outer edges of said flaps with the outer edge of said tab body and each having a substantially continuous curved shoulder in en-

gagement with the peripheral edge of the record, and a tab handle comprising a portion of said tab body projected outwardly therefrom intermediate said flaps and beyond the peripheral edge of the record, said flaps and tab body being tensioned slightly toward each other, said U-shaped ends being constructed and arranged to produce a clamping effect upon said edge of the record, and said tab body having markings thereon for identifying the record.
